[57] **CLAIM**

The ornamental design for a garden lighting fixture, as
shown.

DESCRIPTION

FIG. 1 is a perspective view of a garden lighting fixture
showing my new design;

FIG. 2 is a front elevational view as seen approximately
from the plane indicated by line 2—2 in FIG. 7;

FIG. 3 is a side elevational view as seen approximately
from the plane indicated by line 3—3 in FIG. 7;

FIG. 4 is a rear elevational view as seen approximately
from the plane indicated by line 4—4 in FIG. 7;

FIG. 5 is a side elevational view as seen approximately
from the plane indicated by line 5—5 in FIG. 7;

FIG. 6 is a top plan view thereof; and,

FIG. 7 is a bottom plan view thereof.
